UNITED STATES PATENT OFFICE

CHARLES C. BLACKMORE, OF DAYTON, OHIO, ASSIGNOR TO THE DAYTON TOY & SPECIALTY COMPANY, OF DAYTON, OHIO, A CORPORATION OF OHIO

BOLSTER FOR TOY VEHICLES

Application filed February 9, 1931. Serial No. 514,446.

This invention relates to a bolster or axle supporting member for a toy vehicle. In toy vehicles the axle is usually supported in openings in a sheet metal bolster which is secured 5 to the body of the vehicle, such as the bed of a coaster wagon. The axle is not supposed to rotate in these openings but in practice it usually does so rotate unless special means are provided for preventing its rotation and 10 in the cheaper class of vehicles it is not practical to provide such means. It frequently happens that the rotation of the axle in the openings of the bolster will result in the edges of the opening cutting into the axle to 15 such an extent as to weaken the same and cause it to break.

One object of the present invention is to provide an axle supporting member, for a toy vehicle or the like, of such a character 20 that the axle will not be injured by its rotation in the supporting member.

A further object of the invention is to provide such a supporting member which may be produced at a low cost and without the 25 use of additional parts.

Other objects of the invention may appear as the device is described in detail.

In the accompanying drawing Fig. 1 is a perspective view of a bolster embodying my 20 invention, showing the axle mounted therein; Fig. 2 is a longitudinal sectional view taken through such a bolster; Fig. 3 is an elevation of the inner side of one of the end portions of the bolster; and Fig. 4 is a detail 25 view of a portion of the bolster showing the bearing opening.

In the drawing I have illustrated one embodiment of the invention and have shown the same as applied to a bolster of a well 40 known type but it will be understood that the invention may take various forms and may be applied to axle supporting members of various kinds.

In the construction here illustrated the 45 bolster 5 is approximately U-shape in form. The transverse portion 6 is provided with bolt holes 7 by means of which it may be secured to the body of the vehicle. The end portions 8 are bent downwardly to an up- 50 right position but are here shown as flared

outwardly so that the lower ends thereof lie in planes on the outer sides of the vertical planes extending through the upper ends thereof. The lateral edges of the bolster are bent downwardly and inwardly to form 55 flanges 9 which reinforce and stiffen the bolster. Each downwardly extending part of the bolster is provided near its lower end with an opening 10 to receive the axle 11 and is also provided with a laterally extending 60 part 12 arranged in line with the edge of the opening and adapted to receive and support the axle. This inwardly extending part is of such a character that it will provide a relatively wide bearing surface for the axle and, 65 further, the construction is such that the opening has no edges which would tend to cut the axle.

The bolster is formed from sheet metal and the laterally extending axle supporting parts 70 are preferably in the form of bosses extruded from the metal of the bolster about the respective openings. The bolster is constructed by first punching out a blank of the proper size and shape, by the use of suitable dies, 75 and in this operation the axle receiving openings 10 are formed and the metal extruded to provide the boss 12. The blank is then formed, on other dies, to impart the desired shape thereto and the inner forming die is 80 so constructed that the boss 12, which extends inwardly from the bolster, between the flanges, will not engage the end of the die or in any way interfere with the completion 85 of the forming operation. This may be accomplished by recessing the ends of the die. Consequently the bolster may be provided with my improved axle support without any additional operation in the production thereof and without the use of additional parts 90 and can therefore be produced at a cost little if any in excess of the cost of producing the ordinary bolster.

While I have shown and described one embodiment of my invention I wish it to be understood that I do not desire to be limited to the details thereof as various modifications may occur to a person skilled in the art.

Having now fully described my invention,

what I claim as new and desire to secure by Letters Patent, is:

In a toy vehicle, an axle supporting member formed of sheet metal, having an axle receiving opening and having the metal extruded about said opening to provide a relatively wide supporting surface for the axle.

In testimony whereof, I affix my signature hereto.
